UNITED STATES PATENT OFFICE.

IRWIN CHASE, OF BAYONNE, NEW JERSEY, ASSIGNOR TO THE ELCO COMPANY, OF BAYONNE, NEW JERSEY, A CORPORATION OF NEW JERSEY.

DESIGN FOR A BOAT-BOLLARD.

46,085.

Specification for Design.

Patented July 14, 1914.

Application filed March 11, 1914. Serial No. 824,069. Term of patent 7 years.

To all whom it may concern:

Be it known that I, IRWIN CHASE, a citizen of the United States, residing at Bayonne, county of Hudson, and State of New Jersey, have invented a new, original, and ornamental Design for Boat-Bollards, of which the following is a specification, reference being had to the accompanying drawings, forming part thereof.

Figure 1 is a front elevation of the bollard showing the glass lense of the light, and Fig. 2 is a rear elevation of the same.

I claim—

The ornamental design for a boat bollard, as shown.

In testimony whereof, I, affix my signature, in presence of two witnesses.

IRWIN CHASE.

Witnesses:

J. G. HANSON,
JULIA M. McCABE.
